UNITED STATES PATENT OFFICE.

CHARLES E. RODERICK, OF BATTLE CREEK, MICHIGAN.

BLOOD-TESTING DEVICE.

Application filed April 20, 1925. Serial No. 24,568.

This invention relates to improvements in blood testing devices.

The main object of this invention is to provide a blood testing device which greatly facilitates the testing or estimating of percentage of hemoglobin in the blood.

A further object is to provide a device of this character which is compact and may be carried as part of a physician's equipment and may be repeatedly used, the gauging indicia being fully protected.

Objects relating to details and economies of construction and operation will definitely appear from the detailed description to follow.

I accomplish the objects of my invention by the devices and means described in the following specification. The invention is clearly defined and pointed out in the claims. 20 A structure which is a preferred embodiment of my invention is clearly illustrated in the accompanying drawing, forming a part of this application, in which:

Fig. I is a front view of my improved blood testing device with a specimen indicated in operative position therein by dotted lines.

Fig. II is a sectional view on a line corresponding to line 2—2 of Figs. III and IV.

30 Fig. III is an edge view.

Fig. IV is a sectional view on a line corresponding to line 4—4 of Figs. I and II.

In the drawing similar reference characters refer to similar parts throughout the several views, and the sectional views are taken looking in the direction of the little arrows at the ends of the section lines.

The embodiment of my invention illustrated comprises a casing made up of a bottom plate 1 having a peripheral upstanding flange 2 thereon. The top plate 3 has a peripheral flange 4 meeting edge to edge with the flange 2. These casing members are secured together by the screws 5.

40 Within the casing I mount an indicia disc 6 having a series of colored gauging segments 7 of varying shades and the segments or sections having numerals associated therewith indicating percentages. The disc is mounted on the rivet 8 which also serves as a gauging means for the casing members.

50 The driving disc 9 has a rim 10 of rubber disposed in engagement with the periphery of the indicia disc so that the indicia disc is driven thereby. This driving disc pro-

jects from the casing at one edge thereof for convenience in manipulation.

The casing has a slight opening 11 in the face thereof disposed so that the indicia segments may be successively brought into register therewith.

The casing has a peripheral slot-like opening 12 in which a strip of paper 13 may be introduced so that a specimen of blood to be tested or gauged may be brought into the sight opening for comparison with the colored gauging segments. This enables the various gauging indicia being brought successively into position for comparison with the specimen, the approximate percentage of hemoglobin being thus very easily determined.

Having thus described my invention, what I claim as new and desire to secure by Letters Patent, is:

1. In a device of the class described, the combination of a casing having a sight opening in the face thereof and a peripheral slot adjacent said sight opening, an indicia disc rotatably mounted in said casing and having colored segments of varying shades thereon with percentage indicia associated therewith, said disc being supported so that the colored segments may be successively brought into register with said sight opening, said slot being positioned so that a specimen may be introduced therethrough for visual comparison with said colored segments, and a driving disc having frictional engagement with said indicia disc, said driving disc being disposed with one edge projecting from the edge of the casing for manipulation.

2. In a device of the class described, the combination of a casing having a sight opening in the face thereof, an indicia disc rotatably mounted in said casing and having colored segments of varying shades thereon with percentage indicia associated therewith, said disc being supported so that the colored segments may be successively brought into register with said sight opening, and a driving disc having frictional engagement with said indicia disc, said driving disc being disposed with one edge projecting from the edge of the casing for manipulation.

3. In a device of the class described, the combination of a casing having a sight opening in the face thereof and a peripheral slot, an indicia disc rotatably mounted in said slot

and having suitable gauging indicia thereon, said disc being supported so that the gauging indicia may be successively brought into register with said sight opening, said slot being positioned so that a specimen may be introduced therethrough for purposes of visual comparison with said gauging indicia, and a driving disc having frictional engagement with said indicia disc, said driving disc being disposed with one edge projecting from the edge of the casing for manipulation.

4. In a device of the class described, the combination of a casing having a sight open-

ing in the face thereof, an indicia disc rotatably mounted in said slot and having suitable gauging indicia thereon, said disc being supported so that the gauging indicia may be successively brought into register with said sight opening, and a driving disc having frictional engagement with said indicia disc, said driving disc being disposed with one edge projecting from the edge of the casing for manipulation.

In witness whereof I have hereunto set my hand.

CHARLES E. RODERICK.
